(74) Attorney, Agent, or Firm — 24IP Law Group;
Timothy R DeWitt(57) **CLAIM**

The ornamental design for a tip tray, as shown and described.

DESCRIPTION

FIG. 1 is a perspective view of a tip tray showing our new design;

FIG. 2 is a top view thereof;

FIG. 3 is a bottom view thereof;

FIG. 4 is a front view thereof; and,

FIG. 5 is a side view thereof.

All sides not shown form no part of the claimed design.
